UNITED STATES PATENT OFFICE.

LOUIS W. DILLON, OF NORTH ATTLEBOROUGH, ASSIGNOR OF ONE-HALF TO
HOMER M. DAGGETT, JR., OF ATTLEBOROUGH, MASSACHUSETTS.

ELECTRIC SWITCH.

SPECIFICATION forming part of Letters Patent No. 399,135, dated March 5, 1889.

Application filed October 3, 1888. Serial No. 287,045. (No model.)

To all whom it may concern:

Be it known that I, LOUIS W. DILLON, of North Attleborough, county of Bristol, and State of Massachusetts, have invented an Improvement in Electric Switches, of which the following description, in connection with the accompanying drawings, is a specification, like letters on the drawings representing like parts.

10 My invention relating to electric switches is embodied in the mechanism for moving the switch-arm by which the contact members of the switch are moved suddenly into and out from the contact, so as to prevent possibility 15 of making an arc between said members or producing heat by the resistance of an imperfect contact between the switch members.

Various devices have been employed for 20 producing a sudden movement of the switch-arm of an electric switch; and the present invention consists, mainly, in the combination of parts hereinafter specified for accomplishing this result.

In the switch forming the subject of this 25 invention the switch-arm is loosely pivoted on a spindle or arbor and extends on both sides of said arbor, so that lateral pressure on said switch-arm at one side of said arbor or pivot tends to turn the switch in one direction, and lateral pressure in the same direction, but at the other side of the arbor or pivot, tends to turn the switch-arm in the opposite direction. The said switch-arm is acted upon at one or the other side of its pivot, according as it is to be moved in one or the other 35 direction by a spring-impelled cam-lever having a cam-surface that co-operates with a stationary projection, shown in this instance as the spindle or arbor upon which the switch-arm turns, by which cam-surface the said actuating cam-lever is retained wholly disengaged from the switch-arm during its movement from one to the other side of the pivot or center of movement thereof, and is moved suddenly and quickly by its actuating-spring into 40 re-engagement with the switch-arm, which is thrown suddenly thereby, the said cam-lever acting wholly as a lever upon the switch-arm, and the stationary projection that co-operates 45 with the cam-surface constituting the ful-

crum on which the cam-lever turns when operating the switch-arm.

A shifting-arm is employed to move the cam-plate from its position in engagement with the switch-arm at one side of its pivot 55 to the position where it engages the switch-arm at the other side of its pivot, the said shifting-arm and the cam-surface of the cam-lever being so constructed that when the cam-lever engages the switch-arm its movement is 60 produced by the spring that acts on the plate, and is independent of the movement of the arm by which it was shifted, so that although the shifting-arm may be turned slowly the switch-arm is always moved promptly and 65 suddenly by spring action.

Figure 1 is a face view of a switch embodying this invention; Fig. 2, a side view thereof; Fig. 3, a longitudinal section; Fig. 4, a detail showing a portion of the switch-arm and its 70 actuating cam-lever, and Figs. 5 and 6 views showing modifications in the electric contacts controlled by the switch-arm.

In the construction shown in Figs. 1 and 2 the switch-arm *a* controls two distinct sets of 75 electric contacts, making two distinct sets of circuit-connections when in the full-line position, Fig. 1, or closed, and removing such connections when moved to the position shown in dotted lines, Fig. 1, or opened; but it is 80 obvious that the movement of said switch-arm may be made to control electric contacts of various kinds, some of which will be briefly referred to hereinafter. The invention is not, however, limited to any particular kind of circuit-connection controlled 85 by the switch-arm *a*, but relates more especially to the mechanism employed for moving the said switch-arm. The switch-arm *a* is loosely pivoted on a spindle or arbor, *b*, which, 90 as best shown in Fig. 3, turns in a tubular bearing-piece, *c*, fastened in the block *A*, of insulating material, that constitutes the base upon which all the parts of the apparatus are supported. One or both ends of said arm *a* 95 co-operate with electric contacts in such manner that when it is in the position shown in full lines, Fig. 1, it makes electrical connection at such contacts, but when in the position shown in dotted lines it breaks such connection.

nection; and in order to move the switch promptly from one to the other of these positions, which will be called the "closed" and "open" positions, respectively, it is actuated by a cam-lever, d , acted upon by a spring, e , and having a cam-surface, d^2 , which guides and controls the position of said cam-lever in its movements, that are produced by the spring c and by an externally-applied actuating force, as will be described. The said cam-surface d^2 is at one side of a curved slot or opening in the lever that embraces a stationary piece or abutment, shown in this instance as the arbor b , upon which the switch-arm a is pivoted, and at an intermediate point between the ends of the curved slot in the lever d the latter is provided with a pin or projection, d^3 , that engages the side of the arm a , and it will be seen that if the cam-lever stands with one end of its slot around the arbor b the projection d^3 will bear on the arm a at one side of its pivot, as shown in full lines, Figs. 1 and 4, but if moved so that the other end of the cam-slot receives the arbor b the said projection d^3 will in such movement, owing to the shape of the cam-surface, follow the path represented in dotted lines, Fig. 4, and the projection d^3 will be carried over, so as to bear on the switch-arm at the other side of its pivot. The spring e acts on the cam-lever in such direction as to tend to keep it with one or the other end of its slot over the arbor b , and when it has been pushed by some extraneous force from either extreme position toward the other the spring will complete the movement from the point where the arbor is about at the middle of the cam-slot. The arbor b constitutes the fulcrum on which the lever d turns, and the said lever is capable of being shifted so that either end fulcrums on said arbor, the cam-surface merely controlling the path of movement of the lever while being shifted with relation to its fulcrum. When the parts are in the position shown in full lines, Fig. 1, the force of the spring e on the cam-lever tends to rotate the switch-arm a toward the contact-plates that co-operate with the ends thereof, and such rotation is limited by the engagement of the switch-arm with the said contact-plates, and the switch-arm is retained by the spring-pressure in its closed position. When, however, the shifting cam-lever has been moved so that its other end fulcrums on the arbor b , the projection d^3 is brought to bear on the arm a at the other side of the pivot and tends to rotate the said arm away from its contacts, and as the arm is not held against such rotation the effect of the spring e will be to turn the cam-lever around the arbor b as a fulcrum, the projection d^3 in such movement also turning the switch-arm until the parts are brought by the action of the spring e into the position shown in dotted lines, Fig. 1, and in full lines, Fig. 6.

In order to conveniently move the cam-lever d with relation to the arbor b , the latter

has fixed upon it arms $f f^2$, which, when the said arbor is turned by a suitable handle, (indicated at b^2 , Fig. 2,) engage the pin d^3 on the cam-lever, which, as shown in this instance, projects at each side of the cam-plate, so as to co-operate both with the arm a , which is at one side, and with the shifting-arms $f f^2$, which are at the other side, of the said cam-lever. This turning of the arms $f f^2$ from the full toward the dotted line position, Fig. 1, tends to carry the projection d^3 from one to the other side of the arbor, and the cam-surface d^2 governs the path of movement of the said projection d^3 , causing it to be first lifted off from the arm a and then applied to the said arm a at the other side of its pivot, as will be understood from the representation in dotted lines in Fig. 4 of the path of movement of said projection. After the arm f has carried the pin d^3 a trifle beyond the middle of the arbor b , as will be effected by the movement of the arm f from the full to the dotted line position, Fig. 1, the spring e , which has thus far been resisting such movement, owing to the curvature of the cam-surface, will immediately continue the movement of the cam-lever until the arbor b is at the other end of the cam-slot, thus throwing the cam-lever suddenly from the position where the pin d^3 is at 2, Fig. 4, to the position where it is at 3, Fig. 4, at which latter position it engages the arm a , striking the same a sudden blow, which, with the continued action of the spring on the cam-lever, moves the switch-arm with great suddenness to the position shown in dotted lines, Fig. 1. In order to close the switch, the arms $f f^2$ are turned in the opposite direction, and the arm f^2 engages the projection d^3 and moves the cam-lever until the middle of its cam-slot has slightly passed the arbor b , when the spring e will complete the movement of the cam-lever suddenly, as before, and in such movement the projection d^3 will throw the switch-arm back to the full-line position, closing the switch promptly. By this construction it will be seen that no matter how slowly the operating-arms $f f^2$ may be turned by the operator the switch-arm is not affected until the cam-lever is suddenly drawn away from whichever arm, f or f^2 , happens to be moving it, and consequently it is impossible to move the switch-arm slowly or to leave the same in an intermediate position, it being always thrown suddenly from its extreme open to its extreme closed position, or the opposite. As before stated, the invention does not depend upon the nature of the contacts controlled by the switch-arm.

As shown in Figs. 1 and 2, each end of the switch-arm is provided with a conducting-sleeve or tubular contact-piece, a^2 , which is insulated from the ends of the arm by bushings of insulated material, a^3 , if the said arm be of metal. The said tubular contact-pieces co-operate with stationary contact-pieces $m m^2$, one pair corresponding to each end of the switch-arm, so arranged as to engage the op-

posite sides of the said tubular contact-pieces a^2 , which thus make electrical connection between the pairs of contacts $m m^2$ when the arm is in the position shown in full lines, 5 Fig. 1, but leave the said contacts $m m^2$ disconnected when the arm is in the dotted-line position, each tubular contact-piece a^2 thus constituting a movable intermediate connection between one pair of stationary contacts $m m^2$, forming the terminals of the circuit controlled by that end of the switch-arm. If desired, the arm itself may form the direct connection between the two contacts $n n^2$, as shown in Fig. 5, which connection is interrupted 10 when the arm is moved to the dotted-line position, Fig. 5; or the connection might be made from the arm itself to one contact, m^3 , as indicated in Fig. 6, in which case the switch-arm a need only be extended at the 15 side of its pivot away from the contact m^3 far enough to be engaged by the pin d^3 for the purpose of opening the switch.

The operative parts of the switch may be inclosed in an inclosing case or shell, as indicated at A^2 , Fig. 2, leaving only the handle b^2 accessible at the outside of the case.

Switches have been made in which the switch-arm is moved by a spring which is applied first at one and then at the other side 20 of the pivot or fulcrum of said switch-arm; but in such switches prior to the present invention the spring acts directly upon the switch-arm and bears against the same while being shifted from one to the other side of 25 the fulcrum, while by the employment of a cam-lever to transmit the impulse of the spring to the switch-arm, as herein described, the spring-actuator engages the switch-arm only at two points, one at each side of the 30 pivot, and is thrown against the switch-arm, striking a blow upon the latter, and thus making its movement much more prompt than when the spring bears constantly against the switch-arm, and has its leverage gradually

increased as it is shifted from its intermediate position to its extreme position at one or the other side of the switch-arm.

I claim—

1. The combination of the pivoted switch-arm with an independently-movable actuating cam-lever that engages the switch-arm at each side of its pivot and a projection or abutment co-operating with the cam-surface and constituting the fulcrum of said cam-lever, by which cam-surface and abutment the 55 said cam-lever is retained wholly disengaged from the said switch-arm during its movement from one to the other side of the pivot thereof, substantially as described.

2. The combination of the switch-arm and arbor constituting the pivot or fulcrum therefor with an independently-movable actuating shifting cam-lever and spring, said lever having a cam-surface co-operating with said arbor, which constitutes the fulcrum for said 65 lever in both positions of the latter, and arms connected with said arbor for shifting the cam-lever relative thereto, substantially as described.

3. The combination of the pivoted switch-arm having contact-surfaces at each end insulated from said switch-arm with a pair of stationary contacts co-operating with the contacts at each end of said switch-arm, and a movable cam-lever that engages the said 75 switch-arm at each side of its pivot, the cam-surface of said lever constituting the guide that determines its path of movement when shifted with relation to the pivot of said switch-arm, substantially as described.

In testimony whereof I have signed my name to this specification in the presence of two subscribing witnesses.

LOUIS W. DILLON.
